(57) **CLAIM**

The ornamental design for a finger-engaged and controlled slicer for dense food products, including cheese, as shown and described.

DESCRIPTION

FIG. 1 is an isometric and perspective view of a finger-engaged and controlled slicer for dense food products, including cheese.

FIG. 2 is a first side perspective view of a finger-engaged and controlled slicer, hereof.

FIG. 3 is a second side perspective view of a finger-engaged and controlled slicer, hereof.

FIG. 4 is a first side view a finger-engaged and controlled slicer, hereof.

FIG. 5 is a second side view a finger-engaged and controlled slicer, hereof.

FIG. 6 is a first end view a finger-engaged and controlled slicer, hereof; and,

FIG. 7 is a second end view a finger-engaged and controlled slicer, hereof.

1 Claim, 4 Drawing Sheets
